UNITED STATES PATENT OFFICE.

ALBERT H. NEILSON, OF TULSA, OKLAHOMA.

PACKING FOR OIL-WELL PUMPS.

Application filed October 30, 1925. Serial No. 65,832.

My invention relates to oil well pumps and more particularly to a packing for sealing the plunger rods of pumps of that type, the principal object of the invention being to provide means for automatically adjusting the packing to the plunger and packing cylinder to compensate for wear during the operation of the pump.

In accomplishing this object I have provided improved details of structure, the preferred forms of which are illustrated in the accompanying drawings, wherein:—

Fig. 1 is a longitudinal view of a pump embodying my improvements, the well, the tubing, the packing cylinder and the coupling being in longitudinal section, and parts of the pump being broken away for better illustration.

Fig. 2 is an enlarged, longitudinal section of the packing cylinder, illustrating application of the packing to the plunger and to the cylinder.

Fig. 3 is an enlarged detail perspective view of the packing elements in spaced but relative relation.

Fig. 4 is a longitudinal, sectional view of the packing cylinder, showing a modified form of packing.

Fig. 5 is a transverse section on the line 30 5—5 (Figs. 2 and 4).

Referring more in detail to the drawings:

1 designates an oil well casing terminating on the roof structure 2 of an oil pool 3, and 4 the tubing which is extended through the casing and through the well hole 5 in the roof structure into the oil pool.

Interposed in the tubing is a packing cylinder 6, connected with the tubing by couplings 7 and 8, and on the lower joint of tubing is a coupling 9 suspending the usual perforated tube 10 through which oil is admitted from the pool. The lower coupling 9 constitutes a seating collar for the standing valve 11, and extending through the tubing and couplings to a point above the standing valve is a hollow plunger 12 containing the usual pumping valves 13 and 14, the upper end of the plunger being operatively connected with a sucker rod 15 in the ordinary manner.

Located within the packing cylinder 6 and surrounding the plunger 12 are packing rings and glands comprising a lower gland 17, an intermediate gland 16 and an upper gland 18, the top gland constituting a com-

bined gland and follower, as presently described.

Each of the glands has an exterior, annular groove 20 containing a split, expandable, metal packing ring 21 adapted for bearing against the inner surface of the cylinder in the usual manner and for the usual purpose.

The bottom gland 17 seats on the top of the coupling 8 and has an interiorly beveled, upper end forming a convex cup 22, and the intermediate gland 16 has a similar, interiorly beveled lower face forming the convex cup 23. Interposed between the glands 16 and 17 is a longitudinally split packing ring 24, the split of which runs diagonally to avoid straight edges along the plunger rod, and the members of the ring 24 have registering, annular grooves 25, containing a contractible metal retaining ring 26 which tends to hold the members of the ring together and in close relation. The ends of the packing ring members are beveled reversely to the beveled edges of the glands 16 and 17 to form convex protuberances 27 and 28 on the ends of the packing ring for seating in the cups 22 and 23 of the glands 16 and 17 so that longitudinal pressure exerted on the glands will tend to press the glands against the ends of the packing ring to draw the members of the packing ring together and against the plunger rod to seal the rod against the flow of oil along its surface.

The gland member 18 and the upper end of the intermediate glands 16 are exteriorly beveled, forming protuberances 29 and 30, and interposed therebetween is a longitudinally split packing ring 31 corresponding to the ring 24 except that the ends of the ring 31 are beveled interiorly to form the cups 32 and 33 into which the protuberances on the glands 18 and 16 project to expand the ring 31 against the surface of the packing cylinder 6 to seal the cylinder and prevent flow of oil between the packing ring and wall of the cylinder. The ring 31 is provided with an annular groove 34, containing a retainer ring 35 for holding its members together.

The combination gland and follower member 18 comprises a sleeve portion 36 of less diameter than the gland portion, and seated about the sleeve and resting on the top of the gland member is an expansion spring 37, the upper end of which surrounds a collar 38.

38 on a packing ring 39 located within the upper end of the tube 6 and seats against said ring to force the heretofore mentioned packing rings and glands together for the purpose described. The ring 39 has an annular groove 40 containing the packing rings 41 in ordinary packing ring construction.

In the modified form shown in Fig. 4, the packing rings are beveled as in the preferred construction, but the glands are oval in cross section, the rounded ends serving to contract or expand the packing rings as in the preferred form.

Assuming the parts to be constructed and assembled as described, the glands and packing rings are held in close relation and under pressure by the spring 37 and weight of the tubing and its contained oil, one set of wedging faces on the glands exerting longitudinal pressure against the interposed packing ring to force that packing ring against the plunger, and the other pair of wedging faces of the glands exerting similar longitudinal pressure against their interposed packing ring to spread the ring outwardly against the surface of the cylinder, one packing ring sealing the plunger and the other sealing the cylinder to prevent flow of oil along the plunger or cylinder.

As the plunger is reciprocated in the packing, wear may occur, which might lessen the seal were it not for the fact that any such wear is taken up by contraction and expansion of the respective packing rings under longitudinal pressure of the glands.

In order to provide for readjustment of the lower packing ring members to compensate for wear, the members of this ring are adapted for slight spread when originally installed, so that the members may be forced together when their inner surfaces have been worn. The expanding ring members need not have the original spacing, as compensation for wear in that case is effected by expansion of the rings rather than contraction thereof.

It is apparent that with my improved construction the pump is packed about the

plunger, as well as against the cylinder and that wear of any of the parts will not result in leakage, the wear being automatically taken up by the adjustable split packing rings.

What I claim and desire to secure by Letters Patent is:—

1. In combination with a packing cylinder and a plunger rod, glands at the ends of the cylinder having concave and convex inner ends, respectively, an intermediate gland having its ends concaved and convexed in paired relation to corresponding faces of the end glands, a packing member between the intermediate gland and the end gland having the concaved face, having its ends convexed to receive compression from said glands, and a packing member between the intermediate gland and the end gland having the convexed face, having its ends concaved to receive expansion from said glands, whereby the packing members are adjustable respectively against the rod and the cylinder.

2. In combination with a packing cylinder and a plunger rod, a bottom gland in the cylinder having a concave seat in its upper end, a gland in the cylinder above the first named gland having a concave seat in its lower end, a split packing ring interposed and filling the space between the glands and having convex protuberances on its ends seating within the concavities of the glands, the upper end of the second-mentioned gland having a convex protuberance on its upper end and a third gland spaced from the second-named gland having a convex protuberance on its lower end, a second split packing ring interposed and filling the space between the second and third-named glands having concave seats in its ends seating the protuberances on said second and third-named glands, the glands and packing rings being grooved circumferentially, and auxiliary packing rings and retention rings in the glands and packing rings respectively.

In testimony whereof I affix my signature.

ALBERT H. NEILSON.
